APPARATUS FOR MOULDING TABLETS OF PLASTIC MATERIAL

Leonard Brook, Leeds, England, assignor to The Forgrave Machinery Company Limited, Leeds, England, a company of Great Britain

Application September 20, 1954, Serial No. 457,110

Claims priority, application Great Britain
October 14, 1953

4 Claims. (Cl. 107—8)

This invention relates to moulding apparatus of the type comprising a rotary die head, rotating on a horizontal axis, for moulding a rope of candy or like plastic stock into a string of formed tablets, each joined to the next by a thin web of stock, a conveyor below the die head for carrying the string of tablets away from the die head in a substantially horizontal path and a guide for guiding the string of tablets from the die head to the conveyor. A machine of this type is described in British specification No. 640,440 dated July 19, 1950.

When production has been started on a machine of this type it is desirable that the string of formed tablets should be maintained clear of the guide so that the conveyor may exercise a slight tugging action on the string to assist in stripping the tablets from the die head. In the case of a belt conveyor, this may be achieved by running the belt at a slightly higher speed than the peripheral speed of the die head, with the result that when the string of tablets has travelled a short distance on the belt it will be lifted clear of the guide. This will either cause the soft tablets constituting the string to be slightly elongated, or will cause the string to slip slightly on the belt. Either of these effects can be tolerated and the desired pull on the string of tablets will be achieved.

The present invention aims to employ, as the conveyor, a chain having pockets shaped to carry the tablets produced by the die head. With such a machine the guide must be so positioned as initially to guide the leading end of the string of sweets into the pockets of the chain in the correct pitch, and it is not possible to cause the string of sweets to lift automatically from the guide by running the chain at a speed slightly higher than that of the die head. On the contrary, it is necessary that the die head and chain should run synchronously to ensure correct feed of the tablets to the pockets of the chain.

The invention provides a moulding apparatus of the above type, in which the conveyor is a chain having pockets shaped to carry the tablets in the string and driven synchronously with the die head and comprising means operable, without other than a momentary interruption of synchronous running of the die head and chain, to free the string from support by the guide so that the string thereafter remains freely suspended between the die head and the chain.

Preferably I provide for a momentary retardation of the die head in relation to the chain. This may be effected by including in gearing driving the die head from the chain, or vice versa, a pair of meshing helical gears, one of which may be shifted axially to impart a momentary acceleration to the chain, or retardation to the die head, so causing the string to lift from the guide.

It will be appreciated that the guide can be arranged, as in the case of British specification No. 640,440, dated July 19, 1950, as a trip device for stopping the machine in the event of the string of tablets adhering to the die head.

2

Two embodiments of the invention will now be described in detail, by way of example, with reference to the accompanying drawings, in which:

Fig. 1 is a diagrammatic front elevation of the die head
5 of the first embodiment,

Fig. 2 is a corresponding side view of the gearing for
driving the die head,

Fig. 3 is a side elevation, partly in section, of the
mechanism for retarding the die head,

10 Fig. 4 is a corresponding plan view, and

Fig. 5 is a side elevation of the second embodiment.
Like reference numerals indicate like parts throughout
the figures.

The moulding apparatus shown in Fig. 1 is of generally
15 similar construction to that described in British specification No. 406,220, dated February 22, 1934. The die head comprises an endless train of moulds constituted by
pockets 10 in a moulding wheel 11, mounted on a horizontal
20 shaft 12, and a series of mould flaps 13. The
shaft 12 of the moulding wheel 11 is driven from a drive
shaft 14, driven by an electric motor (not shown) through
the agency of a pair of helical gears 20, 21 and a pair
of spur gears 22, 23. The mould flaps 13 are pivoted
25 on a wheel or chain (not shown) driven synchronously
with the shaft 12.

Normally the flaps 13 occupy the position shown at
the left hand side of Fig. 1. As they approach the
moulding wheel they are moved inwardly by a cam 15
30 and as they pass over the moulding wheel they are held
down by a cam 16, as shown. The flaps 13 thus cooperate
with the moulding cavities 10 to mould the rope 17
35 of boiled sugar or like stock which is fed into the machine.
After the flaps 13 leave the cam 16 they are moved
outwardly again by a member 18. The rope 17 of sugar is thus moulded into a string 19 of tablets, each
40 joined to the next by a thin web of stock, which breaks
easily when the sugar has cooled. The apparatus may
include cams for causing inward movement of lateral
dies to mould or emboss the ends of the tablets as de-
scribed in British specification No. 406,220, dated Febru-
ary 22, 1934.

The string 19 of tablets is delivered in a downward
direction from the die head to the upper horizontal run
45 of a conveyor chain 24, passing over sprockets, not
shown, one of which is driven from the drive shaft 14.
The chain 24 has pockets 25 shaped to carry the tablets
in the string 19.

Initially the tablets are guided on to the chain 24 by
50 a guide 26 as shown in full lines in Fig. 1. The string
of tablets can, however, be lifted clear of the guide 26,
and caused to assume the position shown in chain dotted
lines in Fig. 1, by imparting axial movement to the
55 helical gear 21 as will now be described. The helical
gear 21 is splined to the shaft 27 supporting it and is
formed with an extension collar 28 engaged by a fork 29.
When the fork 29 is shifted from the full line position
of Fig. 2 to the chain dotted position, the die head will
60 receive a slight anti-clockwise rotation due to the helix
angle of the teeth on the gears 20, 21. As the die head
is rotating in a clockwise direction, it is accordingly
retarded momentarily in relation to the conveyor chain,
thus causing the string of tablets to lift from the guide 26.

As shown in Figs. 3 and 4, the fork 29 is carried by a
65 bracket 30 fitted to the lower end of a spindle 31 mounted
to rotate in a bush 32 secured to the machine framework.
Fixed to the upper end of the spindle 31 is a cap 33,
to which is pivoted at 34 a manually operable lever 35.
The helical gear 21 is shown in Figs. 3 and 4 in the position
70 shown in full lines in Fig. 2, i. e. the position it
occupies at the start of a run. The lever 35 then occupies
the position shown in full lines in Figs. 3 and 4,

in which it is held by engagement of a detent 36 on the lever with a notch 37 in the sleeve 32. When it is desired to shift the helical gear 21 to the position shown in chain dotted lines in Fig. 2, the lever 35 is swung anticlockwise (as seen in Fig. 3) about its pivot 34 against the action of a spring 38, thereby disengaging the detent 36 from the notch 37. This frees the spindle for rotation by the lever 35 in an anticlockwise direction as seen in Fig. 4 to shift the helical gear 21 axially to the extent required to retard the die head and cause the string 19 of tablets to lift from the guide 26 (Fig. 1). The lever 35 is retained in its shifted position by engagement of the detent 36 with another notch in the sleeve 32.

It will be appreciated that, if desired, the string of tablets could be caused to lift from the chain by imparting a momentary acceleration to the chain. In this case the arrangement so far described is modified as indicated in Fig. 5 by applying the drive from the electric motor through a sprocket 113 to the shaft 112 of the die head and shifting the helical gear 21 as described above in the direction of the arrow A to impart a forward movement to the gear 20 and therefore a momentary acceleration to the chain which is driven from the shaft 114 by a sprocket 115.

In each of the illustrated embodiments an increase in tension is applied to the string 19 of tablets to cause it to lift from the guide 26 as the result of the momentary variation in the relative speeds of movement of the die head and the chain caused by the shifting of the helical gear 21.

The arrangement illustrated is advantageous because it is desirable that the guide 26 should be associated, as described in British specification No. 640,440, dated July 19, 1950, with a trip mechanism for stopping the machine in the event of the tablets sticking in the pockets 10 of the moulding wheel 11, the trip mechanism being actuated in this event by pivotal movement of the guide.

What I claim as my invention and desire to secure by Letters Patent is:

1. In a machine for moulding tablets from a rope of plastic stock, in combination, a die head rotatable on a horizontal axis and formed with mould cavities, means coacting with said die head to mould the rope into a string of tablets each joined to its neighbors by a thin web of stock, a chain conveyor extending in a substantially horizontal path below the die head, driving mechanism for driving said chain and said die head synchronously, said chain having pockets spaced along its length and shaped to receive and carry the tablets in the string, a guide, inclined downwardly from the open sides of the mould cavities in the die head to the open sides of the pockets of the chain, which guide is operative when the machine is started to guide the string of tablets into the pockets of the chain, and means operable while the machine is running to adjust said driving mechanism to create a momentary variation in the relative speeds of movement of the die head and the chain and thereby to effect momentary acceleration of the chain in relation to the die head.

2. In a machine for moulding tablets from a rope of plastic stock, in combination, a die head rotatable on a horizontal axis and formed with mould cavities, means coacting with said die head to mould the rope into a

string of tablets each joined to its neighbors by a thin web of stock, a chain conveyor extending in a substantially horizontal path below the die head, driving mechanism for driving said chain and said die head synchronously, said chain having pockets spaced along its length shaped to receive and carry the tablets in the string, a guide, inclined downwardly from the open sides of the mould cavities in the die head to the open sides of the pockets of the chain, which guide is operative when the machine is started to guide the string of tablets into the pockets of the chain, and means operable while the machine is running to adjust said driving mechanism to vary the relative speeds of movement of the die head and the chain and thereby to effect momentary retardation of the die head in relation to the chain.

3. In a machine for moulding tablets from a rope of plastic stock, in combination, a die head rotatable on a horizontal axis and formed with mould cavities, means coacting with the die head to mould the rope into a string of tablets each joined to its neighbors by a thin web of stock, a chain conveyor extending in a substantially horizontal path below the die head, said chain having pockets spaced along its length and shaped to receive and carry the tablets in the string, means for driving the chain, gearing driving said die head from said chain and including a pair of meshing helical gears, a guide, inclined downwardly from the open sides of the mould cavities in the die head to the open sides of the pockets of the chain, which guide is operative when the machine is started to guide the string of tablets into the pockets of the chain, and manually operable means for shifting one of said gears axially in relation to the other gear and thereby to effect momentary retardation of the die head in relation to the chain.

4. In a machine for moulding tablets from a rope of plastic stock, in combination, a die head rotatable on a horizontal axis and formed with mould cavities, means coacting with said die head to mould the rope into a string of tablets each joined to its neighbors by a thin web of stock, a chain conveyor extending in a substantially horizontal path below the die head, driving mechanism for driving said chain and said die head synchronously, said chain having pockets spaced along its length and shaped to receive and carry the tablets in the string, a guide, inclined downwardly from the open sides of the mould cavities in the die head to the open sides of the pockets of the chain, which guide is operative when the machine is started to guide the string of tablets into the pockets of the chain, and means operable while the machine is running to adjust said driving mechanism to create a momentary increase in tension in the string of tablets, thereby causing said string of tablets to lift from said guide.
